UNITED STATES PATENT OFFICE

WILLIAM HENRY BERRISFORD, OF STOKE-ON-TRENT, ENGLAND, ASSIGNOR TO LOCKWOOD'S CLEAN COAL PROCESS LIMITED, OF LONDON, ENGLAND

APPARATUS FOR SEPARATING COAL FROM DIRT AND LIKE FOREIGN SUBSTANCES

Application filed January 3, 1930, Serial No. 418,329, and in Great Britain November 17, 1928.

This invention relates to improvements in means for separating coal from dirt and stone or other foreign substances mixed therewith—hereinafter for convenience referred to 5 as stone—and more particularly to apparatus of the type comprising inclined sheets of hard material, preferably glass, on to which the material to be separated falls from an intervening step, roller or other means of feeding 10 the mixture so that the pieces bounce to some extent down the inclined sheets and are separated mainly by reason of differences in specific gravity which affect the length of bounce of the respective materials. The sheets of 15 glass or the like are separated from each other at their adjoining edges to leave a gap over which the coal jumps whilst the stone passes downwards through the gap. For further separation of any coal which passes down- 20 wards through the gap, a second and even a third series of inclined plates is employed.

The object of the present invention is to provide an improved form of plate which will effect a more thorough separation of the 25 coal and stone.

Hitherto the inclined plates have been plane, with or without a curved tip, and according to my invention I form such a plate—substantially arcuate in side elevation or a 30 combination of arcuate and plane portions so as to have as general contour a continuous curve and place it at the desired angle of inclination, the coal and stone thus falling into what is in effect a shallow dish-like plate 35 set at the necessary angle.

The impulse imparted to the mixture of coal and stone causes it to pass down the first part of the plate and then due to the arcuate shape of the plate the mass gradually assumes 40 a more horizontal direction of travel until it is travelling substantially horizontally just before it reaches the gap between the plates. This disposition may be varied as desired, however. The invention can be applied either 45 to a single stage or to a multi-stage separator; in the former case a single plate is employed, the separated stone passing over the end of the plate to a discharge chute located below the edge of the plate while the coal 50 passes to a second discharge chute which ad-

joins the first chute at its side remote from the said edge. In the case of a multi-stage separator, any inclined plate in the apparatus whereon a mixture of coal and stone is to fall and from which the mixture proceeds over a 55 gap, may be formed as described.

The improved form of plate may be made of any suitable material, glass, steel, alloy or the like and the coal may be fed to it in any regular manner, similar to those described. 60

The invention is illustrated in the single figure of the accompanying drawing as applied to a single stage separator.

1 is the plate which is of arcuate form in section and is formed of glass, steel, alloy 65 or other suitable material. The plate is secured to wooden bearers 2 mounted on a bracket 3 pivotally mounted at 4 to the frame 5 of the separator and engaged by a cam 6 secured to an operating shaft 7 rotation of 70 which effects an adjustment of the setting of the bracket 3 and hence of the plate 1.

8 is a "stone" chute the mouth of which is located below and slightly to one side of the delivering end of the plate 1 and 9 is a "clean 75 coal" chute the mouth of which adjoins the mouth of the chute 8 and is remote from the delivering end of the plate 1. The dirt chute 8 may conveniently comprise an adjustable plate 10.

The constructional work supporting the conveyor feeding the cleaning apparatus is shown at 11, and 12 is the end of the conveyor itself.

As the mixture of coal and stone passes 85 down the first part of the plate it gradually assumes an increasingly horizontal direction of travel until just before it reaches the end of the plate a substantially horizontal direction of travel is assumed.

Obviously the invention can be applied to a multi-stage conveyor, the coal passing down the chute 9 to one or more plates which if desired may be of the form according to the invention.

What I claim is:—

1. Separating apparatus of the class described comprising a plate onto the upper surface of which the materials are adapted to fall, means pivoting said plate adjacent its 100

discharge end for movement on a horizontal axis, cam means cooperating with the plate rearwardly of said axis operable to adjust the position of the plate, said surface being substantially arcuate in the line of travel of the materials from the zone of reception thereof to the said discharge end, and said surface at the discharge end being arranged substantially horizontal.

- 10 2. Separating apparatus of the class described comprising a plate onto the upper surface of which the materials are adapted to fall, a supporting frame, a bearing on said frame, a bracket, a shaft pivoting said bracket to the bearing adjacent the discharge end of the plate, bearers on said bracket for said plate, the upper surface of said plate being substantially arcuate in the line of travel of the materials to be separated from the zone of reception thereof to said discharge end, the said surface at the latter end being substantially horizontal, means on the frame to adjust the plate on said shaft arranged rearwardly of the shaft, and chute means for separated material arranged on said frame with their entrances forwardly of the discharge end of the plate.

In testimony that I claim the foregoing to be my invention, I have signed my name
30 this 20th day of December, 1929.

WILLIAM HENRY BERRISFORD.
